[57] CLAIM

The ornamental design for a Tai Chi emblem bowling ball,
substantially as shown and described.

DESCRIPTION

FIG. 1 is a perspective view of a Tai Chi emblem bowling ball
showing my new design;

FIG. 2 is a top view of the Tai Chi emblem bowling ball of
FIG. 1 the bottom being a mirror image of the top; and,
FIG. 3 is an enlarged side view of the Tai Chi emblem
bowling ball showing my new design.

The drawings are lined to indicate contrasting color.
